DESIGN FOR A LACE

Joseph Persky, New York, N. Y.

Application February 18, 1936, Serial No. 61,222

Term of patent 3½ years

To all whom it may concern:

Be it known that I, Joseph Persky, a citizen of the United States of America, residing in city of New York, county of New York, and State of New York, have invented a new, original, and ornamental Design for a Lace, of which the following is a specification, reference being had to the accompanying drawing, forming part thereof.

The figure in the drawing is a plan view of a lace embodying my new design.

The design unit is contained between the vertical broken lines, which unit is repeated in regular succession as indicated by the extensions beyond the unit boundaries.

I claim:

The ornamental design for a lace substantially as shown and described.

JOSEPH PERSKY.
